UNITED STATES PATENT OFFICE.

ROBERT D'UNGER, OF CHICAGO, ILLINOIS, ASSIGNOR OF FOUR-TENTHS TO
WILLIAM L. COPELAND, OF SAME PLACE.

TELEPHONIC TRANSMITTING-INSTRUMENT.

SPECIFICATION forming part of Letters Patent No. 390,575, dated October 2, 1888.

Application filed January 9, 1888. Serial No. 260,168. (No model.)

To all whom it may concern:

Be it known that I, ROBERT D'UNGER, M. D., of Chicago, Illinois, have invented certain new and useful Improvements in Telephonic Transmitting-Instruments, of which the following is a specification.

The principal object of this invention is to provide a transmitting-instrument for long-distance communication. Other objects of the invention will be apparent from the subjoined description.

The invention consists in applying the principle of leverage to increase the effect of the vibrations of the diaphragm; also, in a means of adjustment of the microphonic contacts; also, in certain other devices or combinations, as specified in the claims at the end hereof.

In the accompanying drawings I have shown so much of a telephonic transmitter containing my invention as is necessary to an understanding of the same.

In the drawings, Figure 1 is a view of the back of the diaphragm, showing the lever and contacts. Fig. 2 is a vertical section through the middle of the diaphragm, but showing the lever and contacts in elevation. Fig. 3 is a top view of the parts in Fig. 1.

In the several figures, 1 is the diaphragm.

2 is a ring to which the diaphragm is secured.

3 is a clamping-ring, which fastens the diaphragm in place on ring 2.

4 are cups on ring 3, one at each side of it.

5 is the base-bar of the lever. It spans the diaphragm, and is provided with fulcrum-points 6, which rest in the cups 4 and constitute a very delicate fulcrum for the lever.

7 is the long arm of the lever. It is mounted on the base-bar 5, which supports it.

8 is a pin on the diaphragm, projecting back toward lever 7, with its end attached to the lever.

9 is a yoke at the upper end of lever 7.

10 is a bar or pencil of carbon or other suitable material supported in the yoke 9.

11 are two ears secured above the yoke 9 to the door or frame to which the diaphragm rings are attached.

12 is a rod mounted in bearings in the ears

11 and capable of turning therein. Its middle portion is bent into a crank, as shown.

13 are rods or pencils of some suitable material, such as carbon. They are strung upon the cranked part of rod 12 so as to hang loosely thereon. Their lower ends rest against the bar 10. By turning the rod 12 the pencils 13 may be inclined more or less, and thus adjusted to bear with greater or less force against the pencil 10.

14 is a milled head on one end of rod 12, by which it may conveniently be turned in making the adjustment.

15 is the usual flaring opening in front of the diaphragm.

16 represents the battery.

17 and 18 are the wires from the terminals of the battery, one connecting with one of the ears 11 and the other with the coil on the main line.

19 is the return-wire connected with ring 3.

20 are wires connecting ring 3 with bar 5 of the lever.

In operation the current passes from the battery through wire 17, ear 11, rod 12, pencils 13, pencil 10, yoke 9, lever 7, bar 5, ring 3, wire 19, coil 22, and wire 18. The vibrations of the diaphragm, amplified by the lever, are transmitted by it to pencil 10, and cause variations of resistance between pencil 10 and pencils 13, thus causing variations of the current.

I of course do not limit myself to the precise form and arrangement of the parts shown and described, as many modifications may be made in them without departing from the spirit of my invention.

What I claim is—

1. The combination, substantially as set forth, of the diaphragm and the amplifying-lever acted upon by the diaphragm and composed of the base-bar 5, having fulcrum-points resting in fulcrum-cups at the side of the diaphragm, and the arm 7, carrying the contact-piece at its free end at a greater distance from the fulcrum than the point of connection with the diaphragm.

2. The combination, substantially as set forth, of the diaphragm, the amplifying-lever

having a yoke, 9, at its free end, the contact-bar 10, supported by said yoke, and the hanging pencils 13, supported independently of the diaphragm and resting against the bar 10.

5 3. The combination, substantially as set forth, of the diaphragm, the lever to amplify its vibrations, the contact-pencil carried by the lever, and the hanging contact-pencils resting against the lever-pencil and adjustable as 10 to their angle of inclination, so as to vary the pressure with which they bear against the lever-pencil.

4. The combination, substantially as set forth, of the diaphragm, the contact-pencil vibrated thereby, the hanging pencils resting against said first-mentioned pencil, and the cranked rod upon which said hanging pencils are hung to adjust their pressure against said first-mentioned pencil. 15

ROBERT D'UNGER.
